STRETCHABLE REINFORCED DIAGONAL FOUNDATION GARMENT

Caroline Brown, New York, N. Y.

Application November 20, 1945, Serial No. 629,795

2 Claims. (Cl. 2-30)

1

This invention relates to foundation garments made particularly of elastic diagonally woven fabric having strands of greater and lesser stretchability.

Broadly, it is an object of my invention to provide a foundation garment made from an elastic fabric woven on the diagonal to provide stretchability in all directions.

More particularly, it is an object of my invention to provide a diagonally woven elastic material having lesser stretchability for the foundation garment made from such material so that certain of the squares or rectangles support certain portions of the body requiring such support.

Another object of my invention is to provide a foundation garment which gives greater freedom of movement to the muscles of the body while supporting the ligaments without causing the wearer any restriction of movement or discomfort.

A further object of my invention is to provide a foundation garment made from a diagonally woven elastic fabric so that the figure is supported at the abdominal region and at the sacral region, providing opposed diagonal pressure upon the said regions.

A further object is to provide a foundation garment having the above mentioned advantages of simple and inexpensive manufacture and of economical use of material.

A further object of my invention is to provide a foundation garment which automatically adjusts itself during periods of fluctuation of weight because of the stretchability of the garment.

A further object of my invention is to provide a foundation garment which will firmly support and persuade the muscles of the body while giving natural freedom of movement of the muscles to the wearer.

Another object is to provide a foundation garment, the main body of which is comprised of two sections of different diagonally woven materials with elastic yarns of different thicknesses seamed together at the opposed sides, providing support at predetermined regions of the body of the person, and providing opposed diagonal pressure upon the abdominal region and the sacral region.

A further object of my invention is to provide a foundation garment made of different materials diagonally woven with heavier and lighter elastic yarns, or woven more closely or further apart, providing squares of greater or lesser elasticity, seamed together at the opposed sides and with a minimum of waste when made into my founda-

2

tion garment, while using a minimum of labor when manufacturing same.

For a fuller understanding of the nature and objects of my invention, reference is had to the following detailed description in connection with the accompanying drawings, in which:

Fig. 1 is a diagrammatic or developed plan view of a diagonally woven elastic material of heavier and lighter elastic yarns or of elastic yarns set closer or further apart and used for the front of my foundation garment.

Fig. 2 is a diagrammatic or developed plan view of a diagonally woven elastic material of heavier and lighter elastic yarns or of elastic yarns set closer or further apart and used for the back of my foundation garment.

Fig. 3 is a front view showing my foundation garment upon the figure.

Fig. 4 is a rear view of the foundation garment shown in Fig. 3.

Fig. 5 is a side view of the foundation garment shown in Figs. 3 and 4.

Referring to Figs. 1 to 4, inclusive, numeral 35 represents a diagrammatic or developed plan view of a diagonally woven fabric of elastic yarns which are uniformly spaced apart and which cross one another at predetermined sections so that a plaid is obtained having sections of greater weight, strength and elasticity and designated D, E and F, respectively, in accordance with the degree of strength of said section. This fabric is a continuously woven fabric having sections which repeat in a predetermined plaid pattern so that the front of my foundation garment shown in Fig. 3 hereinafter mentioned and described can be cut. Fig. 2 shows a similar type of fabric used for the back of the garment pictured in Figs. 3, 4 and 5. The section D has the weakest strength, E has greater strength than D, and F has greater strength than either D or E.

The dash lines 36 represent the top cutting line of the front of the garment while the dash lines 37 represent the cutting line of the bottom of the front of the garment. In Fig. 2 the dash lines 38 represent the top cutting line of the back of the garment and the dash lines 39 represent the bottom cutting line of the back of the garment.

Figs. 3, 4 and 5 show a foundation garment formed from fronts cut from fabric 35 shown in Fig. 1 and backs from the continuous fabric shown in Fig. 2. Figs. 3, 4 and 5 show the relative position of the plaids representing the different strength of the units as they appear on the human form. The garment shown in Figs. 3, 4 and 5 is comprised of a front and back, seamed ver-

tically at both sides and is formed from two pieces of material, each being woven in a differently arranged plaid.

Fig. 3 shows the front view of my modified garment upon the human figure, section 40F representing a square in diagonal position having greatest strength and so positioned upon the body that pressure is applied to the abdominal region in order to support the abdominal muscles with the same advantages as described for section 12C. Sections 41E and 42E being of lesser strength or having greater stretchability than section 40F, cover the hips of the wearer giving support to the ligaments and muscles of such portions without constricting or interfering with the normal movements of such ligaments and muscles. Section 43D has the greatest stretchability and is positioned over the lower abdominal region and upper thighs at the center front in order to provide the greatest freedom of movement for the legs. Sections 44E and 45E are sections of lesser strength than section 40F, giving support to the thorax or rib section and causes the garment to hug the figure preventing its riding either up or down and maintaining the garment in its proper position upon the wearer, and further retaining the garment in its original shape. Section 46D has the most or greatest stretchability and falls in the center at the upper front in order to give freedom for breathing and to relieve any pressure at the chest which may interfere with normal breathing. The upper portion of the garment may be cut in V-formations on the diagonal and with the weave to provide for brassière cups to fit within such V-shaped cut outs as shown by dot and dash lines 47.

Fig. 4 shows the back of the garment with section 48F of least stretchability covering the lower back central portion and giving the greatest support to that portion of the body. Sections 49E—49E being of medium stretchability, stretch with the muscles to support the back to aid in relieving fatigue of the wearer. The upper back of the garment is cut diagonally with the weave and has greatest stretchability so that the movement of the shoulders cause the ligaments of the back to stretch diagonally making it necessary to provide both support and a great deal of stretchability for that portion. Furthermore, providing a low cut back is preferable for wear with low cut outer garments. Section 50D having greatest stretchability is provided at the lower rear portion to give adequate stretchability especially when the figure is bent or seated. Sections 55E cover the gluteus muscles and support same.

The arrows shown in Fig. 5 indicate the opposed diagonal pressures upon the regions to which such arrows are pointed indicating support at the abdominal region and the sacrum region; the dot and dash lines 51 and 55 indicate the V-shaped cut outs for the lower portions of the garment; the points of which receive garters 52—52, 53—53, and 54—54.

The edges horizontally shown of Fig. 1 are joined to the edges horizontally shown of Fig. 2. The units indicated by dash lines 36, 37, 38 and 39 are joined either by stitching or known fastening means, similar slide fastener units may be attached to one of said seams for opening the 70 garment when desired.

This type of foundation garment hereinbefore described, because it hugs the figure and stretches with the muscles due to the diagonal position of the weave, can be used without shoulder straps. 75

This is of advantage when certain types of outer garments are worn where shoulder straps would be unsightly and would mar the beauty of the ensemble. Certain types of stout women who

have difficulty in wearing shoulder straps which irritate and cut the shoulders would prefer a strapless foundation garment. It is well known in the art to give certain support to portions of the foundation garment such as the brassière to aid in maintaining such a garment in proper position when shoulder straps are not used. Of course, shoulder straps as shown in the figures may be used either as shown or in different positions such as crossed, or in any other desired position.

It should be noted that the weave of the material is placed on the diagonal since virtually all of the muscles of the body stretch diagonally except where sections 40F and 48F cover the body in order to give greatest support at such portions.

It is obvious that various changes and modifications may be made in the details of construction and arrangement of parts without departing from the general spirit of the invention.

25 I claim:

1. A foundation garment of the character described, the main body of which is made from material woven on the diagonal of elastic strands, said material having a series of squares and rectangles of greater and lesser stretchability and so positioned in said foundation garment that portions of the material of least stretchability cover the abdominal region and the sacral region providing opposed diagonal pressure upon said 30 regions, portions of said material of greater stretchability than said first named portions cover the hips and sides of the body, and a portion of said material of greatest stretchability than said first two named portions covers the lower 35 abdominal region and upper thighs at the center front.

2. A foundation garment made from diagonally woven elastic material having sections in the form of squares and rectangles of three degrees of strength and elasticity, the abdominal region, the thorax or rib sections, the gluteus muscles and the sacral region of the wearer being covered by square diagonal portions of greatest strength and least elasticity, the hips, the lower part of the chest, and part of the back being covered by rectangular diagonal portions of lesser strength and elasticity, the lower abdominal region and upper thighs, the center of the chest and the upper portion of the back being covered by square diagonal portions of greatest elasticity and least strength, providing different degrees of support to the said different portions of the body of the wearer without restricting the muscles and ligaments.

60 CAROLINE BROWN.
